UNITED STATES PATENT OFFICE.

WILLIAM E. BARNUM, OF PORT MOODY, BRITISH COLUMBIA, CANADA, ASSIGNEE OF
ONE-HALF TO JOHN ALEXANDER McCONNELL, OF PORT MOODY, CANADA.

GAS ECONOMIZER.

Application of December 21, 1921. Serial No. 523,957.

To all whom it may concern:

Be it known that I, WILLIAM E. BARNUM, citizen of the Dominion of Canada, residing at Port Moody, in the Province of British

5 Columbia, Canada, have invented certain new and useful Improvements in Gas Economizers, of which the following is a specification.

This invention relates to a gas economizer 10 for internal combustion engines of the four-cycle class having a closed crank-case.

In engines of this class a considerable waste of fuel occurs by leakage past the pistons into the crank-case during their compression stroke and past the valve push rods, which leakage it is the object of this invention to retrieve and use.

The invention is particularly described in the following specification, reference being 20 made to the drawings by which it is accompanied, in which:

Fig. 1 is a vertical section on the line 1—1 in Fig. 2, and

Fig. 2 is a sectional plan on the line 2—2 25 in Fig. 1.

The device comprises a small cylinder 2, one end of which is closed as at 3, and the other is flanged to receive a cylindrical drain cup 4 of diameter corresponding to that of 30 the cylinder. Across the joint between the cylinder 2 and the drain cup 4 is a gauze screen 5 and secured in the same joint and projecting concentrically within the cylinder 2 is a cylindrical screen 6 having a closed upper end.

To the body of the cylinder 2, connection is made at 7 with the crank-case of the engine, and at 8 with connections from the valve push rod chambers. To the same cylinder, connection is made at 9 from the radiator above the water level and at 10 connection is made to the intake manifold of the engine.

The lower part of the drain cup 4 is connected at 11 to the engine exhaust pipe or manifold 13, which connection is closable with a stop-cock 12.

In operation, the suction of the engine intake connected at 10 induces a flow thereto 50 of gas and air from the crank-case, through the connection 7, and from the valve push rod chamber through the connection 8, also a proportionate amount of aqueous vapour through the pipe 9 from the radiator. These 55 are effectively mixed in the cylinder 2 be-

fore delivery to the gas intake to the cylinder, and a considerable loss of gas through leakage is thereby retrieved and favourably used.

The gauze screen 6 prevents short circuiting and tends to equalize the flow from the several connections, and, with the screen 5, prevents the possible ignition of the gas by the connection to the exhaust when that connection is made.

65 The drain cup 4 is designed to receive any water that may be carried over from the radiator into the cylinder 2. It may be periodically withdrawn from the cup or the drain cock 12 may be left slightly open that it may drain continuously.

In applying the device it will preferably be placed immediately adjacent the exhaust manifold, so as to derive heat by conduction therefrom.

75 The device is formed to effect a considerable saving in the oil used, and its connection to the radiator by indrawing and mixing with the gas a small quantity of water vapour is an effective prevention of carbon 80 deposit in the cylinders.

Having now particularly described my invention, I hereby declare that what I claim as new and desire to be protected in by Letters Patent, is:

85 1. In an internal combustion engine, means for drawing gases severally from the crank-case, the push rod chambers and the upper part of the radiator into a mixing chamber, means for mixing them in the presence of 90 heat drawn from the exhaust, and means for delivering the mixed gases into the intake of the engine.

95 2. A mixing chamber for an internal combustion engine, said chamber horizontally jointed adjacent the lower end, a transverse gauze screen secured in the dividing joint, means for connecting the upper part of the chamber to the crank-case, the push rod chambers and the upper part of the radiator, 100 and to the intake of the engine, and means in the lower part of the chamber for re-evaporating the water of condensation therein.

105 3. A mixing chamber composed of two parts horizontally jointed adjacent the lower end, a transverse gauze screen secured in the joint, means for connecting the upper part of the chamber to the crank-case, the push rod chambers and the upper part of 110

the radiator and to the intake manifold of the engine respectively, and means for connecting the lower part of the chamber below the transverse screen to the exhaust of said engine.

4. A mixing chamber composed of two parts horizontally jointed adjacent the lower end, a transverse gauze screen secured in the joint, means for connecting the upper 10 part of the chamber to the crank-case, the push rod chambers and the upper part of the radiator and to the intake manifold of the engine respectively, and means for connecting the lower part of the chamber below 15 the transverse screen to the exhaust with means for controlling passage through the exhaust connection.

5. A mixing chamber for an internal combustion engine horizontally jointed adjacent the lower end, a transverse gauze screen secured in the joint, a wire gauze baffle secured in the joint and conforming to the walls of the upper part of the chamber a short distance from them, means for connecting the upper part of this chamber without 20 the gauze baffle to the crank-case, the 25

push rod chambers, and to the upper part of the radiator, and to the intake manifold of the engine respectively, and means for re-evaporating the water of condensation from 30 the lower part of the chamber.

6. A mixing chamber for an internal combustion engine horizontally jointed adjacent the lower end, a transverse gauze screen secured in the joint, a wire gauze baffle secured in the joint and conforming to the walls of the upper part of the chamber a short distance from them, means for connecting the upper part of this chamber without 35 the gauze baffle to the crank-case, the 40 push rod chambers, and to the upper part of the radiator, and to the intake manifold of the engine respectively, means for re-evaporating the water of condensation from 45 the lower part of the chamber, and means for draining and re-evaporating the water of condensation from the lower part of the chamber by connection of the same to the exhaust of said engine.

In testimony whereof, I affix my signature.

WILLIAM E. BARNUM.
